JAMES B. GARNER AND SYLVESTER C. PRESTON, OF PITTSBURGH, PENNSYLVANIA, ASSIGNORS, BY MESNE ASSIGNMENTS, TO HOPE CONSTRUCTION AND REFINING COMPANY, OF PITTSBURGH, PENNSYLVANIA, A CORPORATION OF DELAWARE.

APPARATUS FOR RECOVERING GASOLINE FROM NATURAL GAS.

Application filed November 21, 1919. Serial No. 339,555.

To all whom it may concern:

Be it known that we, JAMES B. GARNER and SYLVESTER C. PRESTON, residing at Pittsburgh, in the county of Allegheny and 5 State of Pennsylvania, both citizens of the United States, have invented or discovered certain new and useful Improvements in Apparatus for Recovering Gasoline from Natural Gas, of which improvements the following is a specification.

In United States Letters Patent No. 989,927, granted to G. M. Saybolt, there is disclosed apparatus for obtaining naphtha or gasoline from combustible gas of natural 15 origin and underground source, that is to say from natural gas. The apparatus, briefly characterized, consists of means for bringing the natural gas when under pressure into absorption contact with a gaso- 20 line-absorbing menstruum, for the purpose of separating from the gas such of its components as are normally liquid at atmospheric temperature and pressure, and in means for subsequently separating from the 25 menstruum the gasoline so absorbed.

The object of our present invention is to improve the apparatus there disclosed and characterized generally as above. The improved process which is accomplished in the 30 operation of the apparatus here described, is described and claimed in a co-pending application, filed June 2, 1919, Serial No. 301,165.

In the practice of our present invention 35 means are provided by which natural gas is passed successively through two bodies of gasoline-absorbing menstruum, preferably a liquid-petroleum hydrocarbon of specific gravity ranging from about 28° to 55° 40 Baume at 60° Fahrenheit, these two bodies of menstruum being circulated and controlled in such manner that largely increased percentages of the gasoline content of the natural gas are economically recovered.

The first body of menstruum through 45 which the gas passes is, by the means presently to be described, so circulated that, preferably in minutely subdivided state, substantially the same bodies of menstruum contact again and again with the advancing

stream of gas. By thus increasing the number of contacts (and preferably increasing also the areas of contact) which the menstruum makes with the gas, we have found that, due to absorption of gasoline from the 55 gas, the Baumé gravity of the menstruum may be raised (that is to say, the specific gravity of the gasoline-laden menstruum may be reduced) in substantially greater degree than has in such processes heretofore been obtained, and a degree such as, with due regard to practical considerations of the entire process, has heretofore been thought impossible of attainment. We have in point of fact found that the Baumé gravity of the menstruum may be raised 8°, and the entire process be otherwise successfully conducted, provided the second body of menstruum through which the gas passes be circulated and controlled in the manner presently to be explained. Among the important advantages of thus building up the Baumé 60 gravity of the menstruum, these incidental ones may be noted: First, much smaller 65 quantities of menstruum are needed for absorbing, carrying and giving up in the still a unit volume of gasoline; and, second, when the menstruum is used in closed cycle, as is the usual practice, the necessary cooling facilities for cooling the menstruum after it 70 leaves the still are of much smaller extent.

We have found that by improving absorption conditions the menstruum as it absorbs gasoline may be caused to pass through 75 relatively wide ranges of Baumé gravity, and accordingly largely increased percentages of the gasoline content of a stream of natural gas may be absorbed. In practice we have found that thus gasoline may be absorbed to a degree nearly approaching the theoretical 80 maximum limit. That theoretical limit is the point where the partial pressure of the gasoline vapor remaining in the gas is equal to the vapor tension of the gasoline 85 in the menstruum. As a specific example, we have found that, conditioned upon proper control of the second body of menstruum already alluded to and described hereinafter, the gasoline may be so completely absorbed 90 from the gas that there will remain in the 95 gas only about fifteen gallons of gasoline 100

per million cubic feet of gas (the gas being measured at a pressure of eight ounces above atmospheric and at a temperature of 60° F.), whereas in the process heretofore usually practiced there still remains in the gas after absorption has been completed, from fifty to ninety gallons of gasoline per million cubic feet of gas, under the same conditions of pressure and temperature.

Still further we have found that, by repeatedly bringing substantially the same bodies of menstruum (we refer to the first body of menstruum) into absorption contact with the stream of gas, the lighter combustible constituents of the gas which, on the initial contact, and before the specific gravity of the menstruum has been substantially raised, are readily absorbed—these lighter constituents are, as the operation progresses and contacts repeated, displaced to a considerable extent by the gasoline content of the gas, properly so called, and these lighter contents are returned to the gas. In consequence, there is a relatively smaller volume of these lighter constituents of the gas carried from the absorption apparatus by the menstruum, and requiring to be released and separated, in order to obtain again gasoline of best quality from the menstruum which carries it.

The second body of menstruum through which, according to our invention, the gas passes, and to which allusion has more than once been made already, is so controlled, and the contact which the gas makes with it so controlled, that the decrease of specific gravity, that is to say, the rise in the Baumé scale, will be but small, as compared with that which is brought about in the first body of menstruum. Preferably the specific gravity of this second body of menstruum is not allowed to decrease more than would be indicated by a rise of 1° in the Baumé scale. We have found that the beneficial results described above, arising from the improved absorption conditions in the meeting of the stream of gas with the first body of menstruum, will be realized only by controlling conditions of absorption in the second body of menstruum to the end just indicated.

The areas of contact between the advancing stream of gas and the first body of menstruum may be increased in any suitable manner:—by means of spray nozzles for example, or by the use of a coke tower as it is called, that is to say, a chamber filled with inert broken material, often lumps of coke, through which the gas ascends while the menstruum percolates downward. The second body of menstruum is preferably maintained in the form of a pool through which the gas bubbles. Such a pool will remove from the gas particles of menstruum carried on in the stream from the first absorber.

It is not necessary, however, that the second body of menstruum be maintained as a pool, and in the sequel it will appear that the second absorber may, for example, be of the coke-tower type.

In the accompanying drawings, the apparatus of our present invention is diagrammatically illustrated. Figure 1 shows a complete lay-out of an operative plant; and Figures 2 and 3 show absorption units such as may be substituted for the units of the form specifically shown in Figure 1.

Referring first to Figure 1, the course of the natural gas from a suitable source of supply and under any desirable pressure is as follows: It comes through a pipe 1 and enters the absorber 2. From absorber 2 it may advance in either of two courses: it may flow through a pipe 6 to absorber 9, which is the second absorber, or it may, passing from absorber 2, flow through pipe connection 11 into the coke tower 12, and from the coke tower 12 pass through the pipe 14 to the second absorber 9. Valves 15, 16 and 17 are provided, so placed, as will be understood on inspecting the drawings, that the stream of gas may flow in either one of the two courses indicated, as may be desired. The absorber 2 is, as shown, preferably a horizontally disposed cylindrical chamber in which, as will presently be explained, the circulation of absorbent menstruum is arrested, and in which there is a minute mingling of gas with menstruum or, stated in other words, where the areas of contact between gas and menstruum are greatly extended. This is accomplished by spraying the menstruum through the advancing stream of gas and, as will be observed, there are in this chamber 2, three sets of spray nozzles for effecting this end, 3, 4 and 5.

The second absorber 9, though as has already been said it need not be, may conveniently be such as shown in Figure 1. This second absorber 9, as here shown, consists also of a horizontally disposed cylindrical chamber in which, as will presently more fully appear, the circulating stream of menstruum is arrested in its flow; and in which it is maintained in a pool; and through which pool the advancing gas is caused to bubble by flowing out through a perforate header 7. It passes out from this absorber by being collected again in another perforate header 8, from which it advances into the pipe line 10, and through the pipe 10 to the point of consumption. The coke tower 12 alluded to needs no elaborate description, in view of what has already been said. It is a tower preferably of cylindrical shape and vertically disposed, filled through the greater part of broken inert material 13, such as stone or coke. The gas is admitted in the lower portion of this tower, and passes upward through the

body of broken inert material, while menstruum introduced in the upper part of the tower, descending, percolates through this same mass of material. This possibility of using or leaving out of use the coke tower is a detail of illustration, serving to show flexibility in the matter of particular apparatus which may be chosen for use.

As has already been intimated, the menstruum in the second absorber and the menstruum in the first absorber are preferably parts of one continuous stream of menstruum flowing in closed circuit, and the line of flow is counter-current to the stream of gas. This preferable arrangement is shown in Figure 1 of the drawings, and the line of circulation of the menstruum will now be followed. Beginning at the pump 18, the menstruum driven by that pump flows through pipe 19 into the absorber 9, where retardation afforded by the enlarged chamber with its contracted exit effects retardation of the stream and formation of the pool of menstruum already alluded to. From the absorber 9 the menstruum is caused to advance through a pipe 21, preferably by means of a second pump 20, and through a continuation 22 of the circulation pipe, into one or another of two lines of flow: either directly through header 25, to which several spray nozzles 3 are attached, into absorber 2, or through a pipe 26 into the top of the coke tower 12, and out again from the coke tower 12, through pipe 28, into the pipe 22 leading to header 25. A proper setting of valves 51, 52, and 53 will determine whether or not the menstruum flowing from the second absorber into the first absorber travels through the coke tower. A pump 27 may be employed in connection with the coke-tower, to pump the menstruum as it passes from the coke tower on into the line which leads to header 25. The construction of the coke tower has been sufficiently indicated, unless it be that it remains to say that the menstruum introduced near the top of the tower is preferably sprayed upon the column of broken material which fills the tower. And this is indicated in the drawing.

From the absorber 2 the menstruum laden with the absorbed gasoline passes into a sump 29, and from sump 29, through a pipe 31 which is controlled by a stop cock 55 41, into a vent tank 42, where such normally gaseous components of the burden incidentally absorbed by the menstruum are, at atmospheric pressure, allowed to escape. From the vent 42 the gasoline-laden menstruum is conveyed to the still 46. It is preferably pumped from vent tank to still, and on its way passes through a heat exchanger 44. Within the still the gaseous burden which the menstruum has carried 60 is separated, and the now denuded menstruum

passes from the still through pipe 47. It enters first the heat exchanger 44, passes thence through the pipe 48 to the cooler 49, and from the cooler flows through pipe 50 to the pump 18, where the circuit 70 described is now completed.

It will of course be understood, and the matter is made plain in the Saybolt specification referred to, that the still, the heat exchanger, and the cooler are introduced 75 in an exemplary way merely, as preferred apparatus by which a gas-carrying menstruum is relieved of its burden, but other appliances might be employed and other principles of separation be resorted to than 80 the heat exchanger and the still. As we have just said, the illustration in this respect is exemplary and no more.

Coming back now to the absorbers 9 and 2, it remains to explain how that condition 85 is brought about which, in the foregoing part of the specification, has already been alluded to: a condition, namely, of relatively great absorption in the first absorber 2 and relatively small absorption in the second absorber 9, with a correspondingly large drop in specific gravity as the menstruum passes through absorber 2, and only a small drop in specific gravity as it passes through absorber 9. This is brought about of course 90 by affording in absorber 2 relatively more favorable conditions of absorption than in absorber 9, and these relatively better conditions of absorption in absorber 2 may consist of either one or both of two absorbing 95 factors: area of contact and time of contact. There is a pipe connection 33 from sump 29 to headers 36 and 37 which, like header 25, lead into absorber 2 through sets of spray jets 4 and 5. In this line of circulation is 100 a pump 32, and by this pump a circulation of menstruum may be completed which in a sense forms an eddy in the flowing stream of menstruum. That is to say, the stream of menstruum advancing through pipe 22 and 105 header 25 into the absorber 2, before it advances from absorber 2 through pipe 31 into the vent, is by means of the pump 32 caused to flow in a closed circuit from absorber 2 through sump 29, pipe 33, header 110 36 and 37, back again into absorber 2. It will be understood that during all the time of operation (at least, with the apparatus arranged as preferred) menstruum will be streaming into absorber 2 and also streaming 115 out through sump 29 and pipe 31, but the condition is such that the main stream flows relatively slowly, while, by reason of the speed of the pump 32, the circulation spoken of as the "eddy" is coursing rapidly, 120 and consequently substantially the same bodies of menstruum are being sprayed again and again into the absorber 2, and again and again come into absorption contact with the advancing stream of gasoline- 125 130

laden gas. It will further be observed that the spray nozzles 3, 4, and 5 provide for minute division of the menstruum as it enters the absorber 2, and so for extended areas of contact in the first absorber between menstruum and gas.

The rates of flow in the various parts of the circuit of menstruum are determined by the several pumps, and particularly pumps 10 18, 20 and 32. The flowing material may be available for test purposes by the provision of a pet cock 24 at the delivery side of the second absorber, and a pet cock 40 at the delivery side of the first absorber. As we have 15 said it is desirable to have a decrease in specific gravity of the menstruum as it passes through absorber 9, such as would be indicated by a rise of 1° in Baumé scale or thereabouts, while in the first absorber it 20 is desirable to have a much greater absorption, such as would be indicated by a rise of 6° or 8° on the Baumé scale, or thereabouts (a rise unprecedented, and but for our improved apparatus impossible). According 25 to tests of material drawn off as the operation progresses at taps 23, 24, and 40, and by means of regulation of speed of the several pumps, the apparatus as a whole may be brought to a condition in which such relative degrees of absorption as we have specified may be brought about.

Referring to the circulation system through the first absorber, which consists of sump 29, pump 32, pipe 33, and its connections, more minute description is desirable. The pipe 33 leads to a header 34, and this header in turn, by means of branch pipes 34 and 35, leads to branch headers 36 and 37, from which the two sets of spray nozzles 40 4 and 5 open. The pipes 34 and 35 are preferably provided with controlling valves 39, and the spray nozzles 5 are preferably constructed to divide the menstruum into a finer spray than do the spray nozzles 4. Preferably also the spray nozzles 4 divide the menstruum into a finer spray than do the nozzles 3. By proper regulation of valves 39, the flow of menstruum through the nozzles 4 and 5 may be controlled, to effect 45 this desired difference in fineness of the spray issuing from the three sets of nozzles 3, 4, and 5, the preferred arrangement being such that the entering gas first meets the finest spray and progressively meets that less and less fine.

The pump 32 is of capacity such and run at a speed such that it causes the menstruum to circulate at a speed to afford, under the existing conditions of valve setting, the desired amount of absorption in absorber 2.

Approximately speaking, the same bodies of menstruum by means of this eddy come again and again in contact with the stream of gas, and, if it be desired to obtain say 65 six contacts of menstruum, or if the men-

strum as it meets the gas is to be (to the extent of five-sixths of its volume) the same body which has already contacted with the gas, the pump 32 will be so operated that the number of gallons of menstruum pumped 70 by it per minute will be six times the number of gallons of menstruum entering the absorber through sprays 3.

Recurring to the matter of the actual figures representing decrease in specific gravity of the circulating stream of menstruum in the first absorber, we have found it to be true that, with natural gas which contains initially about five hundred gallons of gasoline per million cubic feet of gas, it is 75 advantageous to effect in the first absorber a decrease in specific gravity such as is represented by a rise of as much as 8° on the Baumé scale. This value may be departed from as circumstances dictate, according as 80 the amount of gasoline carried in the gas varies.

In the ensuing claims we speak of a first body of menstruum and a second body of menstruum, and by the second body of menstruum we mean that in the absorber 9. By the first body of menstruum we mean that in the absorber 2, together with (in case it be used) that in the coke tower 12.

It remains to be shown that the apparatus used admits of variation in the specific form. Referring to Figure 2, there will be seen illustrated in it an alternative form for the second absorber, that is the absorber which in Figure 1 is marked 9. In this case this second absorber takes the form of a coke tower 56 of familiar construction, sufficiently described already. The circulating menstruum entering through the pipe 19^a is subdivided, and caused to percolate through 100 the body of broken inert material 57. Descending through this it gathers at the bottom of the tower and passes on through the pipe 21^a to the first absorber. At the same time, the gas from the first absorber enters the coke tower 56 through pipe 6^a and rises 105 through the body of inert broken material 57, where it gives up substantially all of its remaining burden of gasoline. From the coke tower it passes on through the pipe 10^a 110 to the point of consumption. In the upper part of the coke tower are arranged baffle plates 59, to detain and return to the stream of menstruum small particles of menstruum which might otherwise be carried on by the gas. More particularly, the details of Figure 2 designated by numerals followed by the letters *a* correspond respectively to the parts which in Figure 1 are designated by the same numerals.

Instead of using separate vessels for the first and second bodies of menstruum, a single vessel may be used, such as, for example, that shown in Figure 3. The single structure wherein the two absorption steps 115 120 125 130

already described are carried on is there shown to be a coke tower 60, provided in the usual manner with a mass 61 of broken inert material.

5. The menstruum enters the tower 60 through the pipe 19^b, and descends percolating through the mass 61, and is collected in the bottom of the tower from which place it may be led either through pipe 30^b to form such 10 a circulation as I have already in connection with the description of Figure 1, characterized by the term "eddy," or through the pipe 31^b to vent tank and still.

A word will suffice to explain the eddy 15 here. A pump 32^b causes the menstruum which flows through pipe 30^b to circulate through pipe 33^b, and enter the coke tower again at a point about midway its height. As before, a rapid circulation through this eddy 20 line will effect the repeated contacts of substantially the same bodies of menstruum again and again with the flowing stream of gas. A vent tank 66 may be placed in this eddy circuit if desired, for the obvious purpose 25 of venting lighter combustible constituents which have been absorbed and carried out of the coke tower in the menstruum. The use of a vent tank at this point does not preclude the use of another vent tank such as 30 42 in Figure 1. One or both may be used as found desirable. And a vent tank 66 may be added, if desired, to the assembly of parts shown in Fig. 1. As before, both pipe connections 30^b and 31^b are at all times open, 35 the circulation is continuous, and it is a matter of controlling the valve ports and the speeding of the pumps which brings about the circulation and absorption which I have already defined. Between the outflow 40 through line 31^b and the inflow through pipe 19^b, the same apparatus for treating the menstruum as that shown in Figure 1, with the variations already suggested, are placed. The gas enters this tower 60 from the line 1^a, 45 flows upwardly, and out through the lead 10^a. In the lower half the stream of gas meets relatively large quantities of menstruum flowing rapidly; in the upper part it meets relatively small quantities of menstruum flowing slowly. The same opportunities 50 are afforded for testing the specific gravity of the menstruum at successive points, in the presence of the pet cocks 23^b, 64, and 40^b.

55 It will be seen that the second body of menstruum may be either in the form of a pool, (Figure 1), or in subdivided state (Figure 3) when brought into contact with the gas. It will further be seen that the first 60 and the second bodies of menstruum may be maintained in the same (Figure 3) or in separate (Figure 1) vessels. It will further be seen that the circulating stream of menstruum may be arrested and dammed (Figure 1) to afford absorbing conditions, or it

may flow without any such backing up of the stream as the use of the term "dam" imports (Figure 3), to afford absorbing conditions. It is clear from the consideration of the apparatus of Figure 1 that a plurality of 70 absorbers may be used to effect the first absorption and, manifestly, without further illustration, the number and type of such a plurality of absorbers may be changed as desired. In all cases, however, there is a small 75 loss in specific gravity of the menstruum passing through the second absorber, as compared with the loss which it undergoes in the first absorber, and means are available for controlling and varying the relative degree 80 of absorption in the two absorbers.

We have found it impossible to absorb from the gas absolutely all of the gasoline which is borne by it, for the reason that the gasoline absorbed by the menstruum will always have a certain vapor tension, and when in the progress of absorption the point is reached where the vapor tension of the absorbed gasoline equals the partial pressure of the gasoline remaining in the gas, absorption 90 will cease. Hence there always remains in the gas after it has passed through the last absorber some vestige of the original gasoline burden. We have found, however, that this remaining vestige may be made 95 very small by the method performed in the apparatus now described.

As a specific example of how completely the gasoline may be absorbed from the gas by the apparatus of our invention, we have 100 in actual operation a plant in which 96.6% of the gasoline burden of the gas is recovered. During a day's run in which this percentage was recovered 19,000 cubic feet of gas were passing per hour through the two 105 bodies of menstruum. The menstruum consisted of liquid petroleum having a gravity before absorption of about 39° B. The pressure of the gas ranged from 56 to 61 pounds above atmospheric pressure, and the temperature under which absorption was performed ranged from 52° to 66° F. The first body of menstruum was circulated, in what I have termed the eddy system of circulation, 110 through the spray absorbers four times as fast as the menstruum from the second absorber entered the first. The loss in specific gravity of the menstruum in the first absorber was that indicated by a rise of 6.7° on the Baumé scale, while the loss in the second 115 absorber was indicated by a rise of 1° on the same scale. The gas before being treated contained 767 gallons of gasoline per million cubic feet, and 741 gallons per million cubic feet were recovered. The apparatus used was 120 of the type and of the arrangement shown in Figure 1 of the accompanying drawings, including the coke tower indicated by numeral 12. 354 gallons of oil per hour were caused 125 to flow through the pool absorber, a rate 130

which, differently stated, is about one gallon of oil to 54 cubic feet of gas.

From what has been said it is apparent that the rate of flow of menstruum is, in 5 the practice of our apparatus, controlled in accordance with the loss of specific gravity in passing through the second absorber. If such loss is greater than is permissible, according to the standards already set, then 10 the conditions of absorption in the first absorber should be modified,—in this case made more favorable to absorption, either by speeding up the eddy circulation or by more finely subdividing the menstruum in 15 the spray. If by such means, correction is not effected, and the loss in specific gravity reduced within permissible range, then the rate of flow of menstruum through the second absorber should be increased. Such an 20 increase of flow of menstruum through the second absorber will mean of course an increased rate of flow through the first. As previously stated, the rate of flow in the line for the eddy circulation, that is through 25 pipe 38, must be correspondingly accelerated, or the fineness of the spray into the second absorber increased, or both of these conditions made more favorable to absorption.

30 In the practice of our invention the gas may be treated under any desired pressure. As compared with the amount of gasoline recovered from the gas when under treatment at the customary pressures of fifty or 35 more pounds per square inch above atmospheric pressure, we have found that as much gasoline may be recovered under a pressure of twenty pounds or less above atmospheric pressure, provided only that the conditions 40 of absorption in the first absorber be sufficiently favorable, and provided that the relative changes in specific gravity in the second absorber be controlled in the manner and to the effect described above.

45 It will be observed that with the apparatus now described the stream of gas, advancing counter-current to the stream of menstruum, meets the stream of menstruum as successive points; that superior conditions 50 of absorption are maintained where the gas initially encounters the menstruum, as compared with the conditions where it ultimately encounters it. These superior conditions result from the formation and maintenance 55 of the eddy in the stream of menstruum so that the same bodies of menstruum come repeatedly into absorption-affording contact with the gas.

It will further be noted that by varying 60 the speed of the pumps according to gravity readings we may cause to vary the absorption conditions of the first contact of gas with menstruum, relatively to those of the ultimate contact.

We have in the foregoing specification 65 described our invention in specific application to an apparatus for recovering commercial gasoline from natural gas. It will be understood, without further elucidation, that it is an apparatus applicable wherever 70 a substance normally liquid is carried in vapor form by gas. In the ensuing claims we make plain the fact that the invention is of such broader aspect. And one thing more should be said: it is not necessary (al- 75 though the matter so stands, when gasoline is being recovered) that the absorbing menstruum be of specific gravity greater than that of the recovered liquid, and indeed in case of the recovery of benzole from the 80 gases which ordinarily carry it in vapor form, the absorbent liquid used will ordinarily be a liquid of less specific gravity than the benzole recovered. Accordingly, in such case, as the operation of our appa- 85 ratus progresses, the menstruum will not, as in the case of gasoline recovery, decrease in specific gravity, but will in fact increase in specific gravity, and in such case it will be understood that the process is accom- 90 plished in so adjusting the apparatus, and so governing the operation relatively part to part, that the specific gravity of that body of menstruum through which the stream of gas first passes will increase (not decrease) 95 through a wider range than will the specific gravity of that portion or body of menstruum through which the gas finally passes.

We claim as our invention:

1. In apparatus for the recovery of a 100 substance normally liquid from a gas carrying it in vapor form, means for forming an eddy in a flowing stream of vapor-absorbing menstruum, together with means for causing a stream of vapor-laden gas to 105 flow first through the eddy and subsequently through the menstruum at a point farther upstream, substantially as described.

2. In apparatus for the recovery of a 110 substance normally liquid from a gas carrying it in vapor form, means for maintaining two bodies of vapor-absorbing menstruum, means for conducting a stream of vapor-laden gas through said bodies of menstruum successively, means for circulating 115 the body of menstruum through which the gas first passes to contact with the gas a plurality of times and means for varying the rate of such circulation independently of any circulation of the other body of 120 menstruum, substantially as described.

3. In apparatus for the recovery of a 125 substance normally liquid from a gas carrying it in vapor form, the combination of two absorbers connected by conduits for gas and for liquid, a gas supply and a liquid discharge conduit communicating with one of said absorbers and a liquid supply and a

gas discharge communicating with the other, a valve in the liquid supply pipe leading to the absorber last named, a bypass for liquid leading from and back again to the absorber first reached by the gas, and means for effecting circulation of liquid in said by-pass, substantially as described. In testimony whereof we have hereunto set our hands.

JAMES B. GARNER.
SYLVESTER C. PRESTON.

Witness:

FRANCIS J. TOMASSON.
